UNITED STATES PATENT OFFICE.

LEOPOLD KABIS, OF CHEYENNE, WYOMING, ADMINISTRATOR OF THOMAS MOORE, DECEASED.

DESIGN FOR A BUCKLE.

SPECIFICATION forming part of Design No. 29,282, dated August 30, 1898.

Application filed July 27, 1898. Serial No. 687,047. Term of patent 14 years.

To all whom it may concern:

Be it known that THOMAS MOORE, deceased, late a citizen of the United States, and a resident of Cheyenne, county of Laramie, and State of Wyoming, duly invented and produced a new and original Design for Buckles, of which the following is a full, clear, and exact description, reference being had to the accompanying drawing, forming a part thereof.

10 The figure is a plan view of a buckle embodying the design.

15 As shown in the drawing, the leading or material feature of the design consists of a skeleton frame composed of the horizontal bar 1 and the short horizontal bar 2, arranged a short distance from the center of said bar 1, and said bar 2 occupies a position parallel with said bar 1. The center of this short bar 2 is slightly

enlarged in diameter, and extending from the outer ends of said bar 2 to the upwardly-curved ends of the bar 1 are the side bars 3. Extending between the ends of the bar 2 and the bar 1 are the bars 4, and extending between the lower ends of said bars 4 and the centers of the side bars 3 are the bars 5. 20 25

What is claimed is—

The design for a buckle, substantially as herein shown and described.

In testimony whereof I affix my signature in presence of two witnesses.

LEOPOLD KABIS,
Administrator of Thomas Moore, deceased.
